E. L. CONNELL

GUARD FOR GRINDING WHEELS

Filed April 15, 1922

Inventor:

Edwin L. Connell,

Albert G. Greene
Attorney.

Patented May 5, 1925.

1,536,565

UNITED STATES PATENT OFFICE.

EDWIN L. CONNELL, OF CLEVELAND, OHIO, ASSIGNOR TO THE VAN DORN ELECTRIC TOOL COMPANY, OF CLEVELAND, OHIO, A CORPORATION OF OHIO.

GUARD FOR GRINDING WHEELS.

Application filed April 15, 1922. Serial No. 553,027.

To all whom it may concern:

Be it known that I, EDWIN L. CONNELL, a citizen of the United States of America, residing at Cleveland, in the county of 5 Cuyahoga and State of Ohio, have invented certain new and useful Improvements in Guards for Grinding Wheels, of which the following is a specification.

My invention relates to improvements in 10 guards for grinding wheels, and has for its object the provision of a simple and adjustable unitary guard for the periphery and sides of emery wheels and the like.

Users of grinding wheels commonly are 15 required to comply with the provisions demanding the protection of the operative by means of a peripheral guard which shall be adjustable as the wheel wears away. Moreover, it is a common requirement that 20 the shaft end or side of the emery wheel, which normally is exposed, shall be boxed or suitably protected.

Accordingly, I have sought to provide the 25 simplest unitary means whereby these features of protection are afforded in a cheap, simple and adjustable guard.

The details of construction and further 30 advantages may best be explained by making reference to the accompanying drawings, wherein:

Figure 1 is a view in side elevation of a 35 grinding mechanism to which my improvements are applied,

Fig. 2 is a front elevation of said mechanism partially broken away, and Fig. 3 is a small elevation.

Throughout the drawings I have employed the same character of reference to indicate the showing of identical parts.

40 A self-contained grinding mechanism, comprising an electric motor *a* and, preferably, two symmetrically positioned, counter-balancing wheels *b* of emery, carborundum or the like, are shown in the drawings for 45 the purpose of explaining my improvements as applied thereto.

A fixed peripheral wheel casing *c* is shown positioned at the left of the motor for accommodating the grinding wheel *b*; this casing being open at the front and side. An adjustable support *d* for the article being ground is positioned upon a bracket *d'* carried by the lower portion of the motor casing.

55 An adjustable guard *e*, terminally slotted

at *e'*, is mounted upon casing *c* by means of thumb-nuts *e''*. This guard comprises an intermediate boxing *e'''* adapted to accommodate the securing nut *d'* at the end of the motor shaft, and the angularly extending 60 peripheral guard *f* adapted to form a barrier at the top of the grinding wheel.

Thus the adjustable guard comprises a 65 suitable boxing for the exposed face of the wheel as well as an adjustable barrier which may be positioned at successively lower levels to conform with the periphery of said grinding wheel as it wears away with use. However, the diametrically positioned guard 70 *e*, while invariably protecting the end of the shaft mounting the grinding wheel, leaves the side of the wheel exposed for lateral grinding thereon. Moreover, as the guard *e* and the transversely extending peripheral 75 guard *f* are integrally formed, there is no chance that one of these members may be forgotten or accidentally displaced when adjustments are required.

It is obvious that these parts may be 80 differently proportioned and mounted, but the adjustable guard preferably combines the protective features for the periphery and shaft or mounting of the grinding wheel along the general lines above explained, conformable with my invention.

Having now described the advantages and structural details pertaining to my invention, I claim as new and desire to secure by Letters Patent, the following:

1. The combination with a grinding wheel, 90 of a main guard casing conforming to and nesting over a greater portion of the periphery of said grinding wheel and exposing a portion of said wheel for grinding purposes, a supplemental guard support upon the end of said main guard and including means for guiding it radially with respect to said wheel, a laterally extending guard plate carried by said supplemental guard support and extending toward the wheel at 95 the end of the main guard, and means for clamping said supplemental guard support in any adjusted position.

2. The combination with a grinding wheel 105 shaft, a wheel and a nut for holding said wheel upon the shaft of a main guard nesting about the periphery of the greater portion of said wheel, and a nut guard member in the form of a strap removably secured to the main guard or opposite sides of said nut.

3. The combination with a grinding device, comprising a shaft, a wheel and a nut for holding said wheel upon said shaft, of a main guard nesting about a portion of the periphery of said wheel, a supplemental guard for one end of said main guard and comprising a solid strap extending diametrically across the main guard and over said nut, means for clamping said strap in place, and a supplemental guard plate carried by said strap and adapted for movement along the end of the main guard toward and from the periphery of the wheel as it wears.

4. The combination with a grinding device, comprising a shaft, a wheel and a nut for holding said wheel upon said shaft, of a main guard nesting about a portion of the periphery of said wheel, a supplemental guard extending along one side of said wheel and over said nut, and a supplemental guard plate carried by said supplemental guard and adapted for movement toward and from the periphery of said grinding wheel.

In testimony whereof I do now affix my signature.

EDWIN L. CONNELL.
